2,198,370

EJECTOR FOR SLUG CASTING MACHINES

Arthur G. Sperry, Hollis, N. Y., assignor to Intertype Corporation, Brooklyn, N. Y., a corporation of New York

Application November 22, 1939, Serial No. 305,595

9 Claims. (Cl. 199—60)

The present invention relates to typographical machines of the general class referred to in U. S. Letters Patent No. 436,532 granted September 16, 1890, wherein composed lines of character bearing matrices are employed for producing printing slugs or type bars, the slugs being cast in a longitudinally slotted mold into which molten type metal is injected at the rear and then being removed or discharged therefrom by means of an ejector which is adapted to advance against the rear or bottom edge of the slug and push it forwardly out of the mold. The modern machines are provided with several molds mounted on a rotatable mold wheel so that one or another mold may be selected for use, and each mold is adjustable as to the length of the casting slot therein in order to produce slugs of different lengths. Further, the height of the casting slots in the several molds may vary so that slugs different in point size or body thickness may be produced.

The present invention relates more particularly to improvements in the slug ejecting mechanism for such machines. Ordinarily this mechanism is adjustable in such manner as to enable the selection of an ejector blade corresponding in vertical width to the length of the casting slot in a selected mold, it being understood that in the ejecting position the casting slot in this particular mold is disposed vertically before the ejector. In order to eject the thinnest slug capable of being cast in the machine, the ejector blades are necessarily very thin and it sometimes happens that in ejecting a thick slug the blade digs into the base of the body portion and thus tends to jam or to twist the slug as it is moved forwardly thereby out of the mold and through the usual trimming knives. This objectionable condition is especially emphasized in the case of the well known recessed or ribbed slugs in which the type carrying portion or shelf overhangs to an appreciable extent the relatively thin body portion, the overhang being supported by widened or thickened ribs spaced at intervals throughout the length of the slugs and projecting laterally from the main or solid body portion thereof.

The object of the present invention is to overcome the objectionable conditions referred to in a simple and effective manner and by means readily adaptable to ejectors of the ordinary forms now in use. To this end the invention provides at least one point in the vertical width of an ejector blade within the usual set thereof a laterally projecting rib preferably made integral with the blade as by staking, welding or otherwise and extending along one side of the blade in a fore

and aft direction so as to increase its effective thickness. The disposition of the rib is such that it falls opposite one of the widened supporting ribs on the slug to be ejected (and of course opposite the recess in the mold which forms such rib on the slug) whereby upon the usual advance of the blade the rib thereon engages against the broad surface presented by the bottom of the corresponding rib on the slug and thus moves the latter forward squarely as it leaves the mold. The invention further contemplates an ejector arranged to accommodate such rib-carrying blades as well as blades of the ordinary plain or non-ribbed type in certain width and arranged also to permit the two types of blades to be interchanged so far as is practicable so that within the single set of blades either a plain or a ribbed blade may be made available. For this purpose the usual blade guiding member or stepped guide at the front of the ejector blade case or housing is provided with suitable slots for accommodating the ejector blades having laterally projecting ribs.

In the accompanying drawing one embodiment of the invention is shown merely by way of example, and obviously many changes and modifications may be made in the form, arrangement and combination of parts without departing from the spirit of the invention. It is to be understood, therefore, that the invention is not limited to any specific form or embodiment except insofar as such limitations are specified in the claims.

Referring to the drawing:

Fig. 1 is a plan view showing a conventional form of ejector slide with a recessed mold, in section, in slug ejecting position relative to the slide, and shows an ejector blade constructed in accordance with the invention in advanced position after ejecting a slug from the mold and between the usual trimming knives.

Fig. 2 is a foreshortened front elevation on an enlarged scale of the ejector blade case shown in the ejector slide in Fig. 1 and shows the stepped guide block at the front of the case modified to accommodate the ejector blades of the invention.

Fig. 3 is a foreshortened side elevation from the right of the ejector blade case in Fig. 2 with the right side plate of core thereof removed, and shows the relation of the rib-carrying blades of the invention to the ribs of a recessed type slug.

Fig. 4 is an elevation in perspective of an ejector blade constructed according to the invention.

Similar parts are designated by the same reference characters in the different figures.

By way of example the invention is herein illustrated as applied to ejector mechanism for slug casting machines which mechanism is constructed in accordance with that described in 5 U. S. Letters Patent 1,123,814 granted January 5, 1915, wherein there is provided a plurality of separate ejector blades usually each of a different width vertically, the blades being arranged side by side in parallel planes in a suitable case which 10 is adjustable sidewise so that any desired blade may be aligned with and operatively connected to a master blade and with the casting slot in the mold, the master blade being actuated periodically in a fore and aft direction to thereby 15 effect slug ejecting movement of the selected blade. Since the construction and mode of operation of such ejector mechanism is well known a full description thereof is deemed unnecessary for present purposes. For complete details, however, reference may be had to the patent above referred to.

As shown in Fig. 1 the ejector blade case 1 containing a single set of ejector blades generally designated A is suitably housed in a widened 25 pocket 2^a in the usual ejector slide 2 (also known as the mold slide), the case 1 being adjustable laterally in the pocket of the slide upon fore and aft movement of a shiftable frame having top and bottom bars provided with obliquely disposed 30 keys (not shown) which operate in corresponding oblique slots 3 in the outer sides of the top and bottom of the case 1. Details of this mechanism are omitted in the present instance but described 35 in the aforementioned Patent No. 1,123,814. Upon adjustment of the case 1 the selected blade 40 of the set thereof contained in the case 1 is brought into the fixed vertical plane in which the master blade 4 secured to the actuating slide 5 is arranged to move fore and aft in known manner 45 when actuated periodically by the ejector link 6. The master blade 4 is of the same thickness as one of the ejector blades A and is provided with a T-shaped tongue 7 projecting from its front vertical edge, such tongue being adapted to engage a correspondingly shaped aperture formed in each 50 of the blades A and to effect operative connection of the master blade to any selected one of the blades A.

The blade case 1 comprises side plates 8 and 55 9, top and bottom plates 10 and 11 and a stepped blade confining guide block 12 at the forward end, these parts constituting means for confining the entire set of blades for lateral shifting movement as a whole and sliding fore and aft movement individually. Different guide blocks may 60 be employed to suit different sets or complements of ejector blades A, the guide block 12 in the present instance being formed with steps to accommodate a single set of twelve blades in nine 65 different widths viz., two blades 30 ems wide, two 26 ems, one 23 ems, one 20 ems, two 18 ems, and one each 15, 14, 12 and 10 ems in width.

According to the present invention one or more 70 of the ejector blades within the set thereof may be provided with a laterally projecting flange or rib to increase its effective thickness. Thus, referring to Figs. 2 and 3, one of the 30 em blades, designated 13, is provided with a lateral rib 14; one of the 26 em blades 15 with a rib 16, and one 75 of the 18 em blades 17 with a rib 18. Fig. 4 shows one of the blades, for example the blade 15 with the rib 16 thereon, this rib member being made integral with the blade proper as by staking, welding or otherwise (for example, as with the blade 18, where the rib constitutes a bent over

portion of the blade itself) and extending along one side of the blade parallel to the top and bottom edges thereof. Fig. 4 also shows the T-shaped aperture 19 into which the tongue 7 on the front vertical edge of the master blade 4 engages to 5 operatively connect the latter to a selected one of the ejector blades in the sidewise adjustable case 1.

It will be noted from Fig. 2 that the bottom edges of all of the blades rest on the bottom 10 or floor plate 11 of the ejector case 1, that the blades have body portions of uniform thickness and are held in close relation facewise by the enclosing side plates 8 and 9 of the case and that they are arranged in orderly relation according 15 to width. However, there is sufficient freedom between the blades to permit any one of them to slide forwardly when keyed to the master blade 4 relative to which the case is adjustable laterally as previously stated. When a selected blade is 20 thus advanced, as it is for ejecting a slug, it is guided and confined facewise by adjacent blades and by the vertical stepped surfaces of the guide block 12, and edgewise by the horizontal steps on the guide block. Thus it will be seen that the 25 top edge of each blade (except for the 30 em blade) terminates adjacent to a horizontal step in the block 12 and one of the blades in every size bears sidewise toward its upper end against a vertical step in the block 12. 30

For accommodating blades which according to the invention carry a lateral rib for increasing their effective thickness, clearance slots for such ribs are cut in the blade guiding edge of the block 12. In the present instance such clearance slots are formed at levels at which lateral ribs would be carried on 30, 26, 21, 18 and 15 em ejector blades for ejecting slugs of these respective lengths, provided that the spacing between the overhang supporting ribs 20 on such slugs 40 is that shown on the slug S. It may be pointed out here that the slug S, which is viewed from its recessed or ribbed side in Fig. 3 and shown in section through one of its ribs in Fig. 1, is representative of a 48-point cast slug in a mold of like 45 size and of a design now in common use. However, the rib spacing on recessed slugs of this and other point sizes may be varied to suit different conditions. As a matter of fact there are several different types of recessed molds in 50 common use but all of them cast slugs of this general character, and the matter of rib spacing is largely governed by requirements of the user. Therefore it will be clear that ejector blades with lateral ribs located differently than those 55 herein shown may be required and in such cases a stepped guide 12 would be provided having clearance slots located at suitable but different levels than herein shown.

As indicated, the lateral ribs 14, 16 and 18 are 60 accommodated in clearance slots 21, 22 and 23 respectively, these slots being coextensive through one of the usual keeper plates 24 which plates overlie the stepped guide 12 at the forward end of the main ejector slide 2 and form 65 between their opposed inner edges a single vertical slot for the passage of the selected blade, such slot also affording guidance and side support to such blade as it advances to eject a slug. Ejector blades may be provided having lateral 70 ribs of suitable projected width for ejecting slugs of greater or less thickness than 48-point, it being understood that the lateral rib on a blade must always be slightly less in width than the depth of the recessed portion in the mold 75

through which it must pass in order to fully eject a slug. However, insofar as possible the clearance slots in the guide block 12 may be made deep enough to suit the widest lateral ribs regardless of the actual projected width of the ribs. Further, clearance slots may be provided for as many rib locations as desired with the exception that for blades which lie close to the right side wall of the blade case there is insufficient space, as will be seen from Fig. 2, to cut such slots in the guide block 12. The guide block 12 in the present instance is provided with additional clearance slots 25 and 26 at suitable levels for accommodating 23 em, 21 em and 15 em blades having laterally projecting ribs thereon. Thus, as will be clear from Fig. 2, the non-ribbed 23 em blade shown may be exchanged for a 23 em blade carrying a lateral rib guided in the slot 25 or the non-ribbed 20 em blade may be exchanged for a 21 em blade with a lateral rib guided in slot 25, and the non-ribbed 15 em blade may be exchanged for a 15 em blade with a narrow rib guided in the slot 26.

The increase in the effective thickness of an ejector blade due to the laterally projecting rib herein provided enables a slug of the thicker variety such as the recessed slug S to be moved forward squarely during its ejection from the mold in which it was cast. In Fig. 1 a mold is shown in slug ejecting position before the ejector slide 2, this mold being one of several secured as usual to the mold wheel 27 which, as well known, is rotatable on a stub shaft carried in an extension of the arm 28 on the slide 2. The mold comprises a cap portion 29 and a body portion 30, the cap being so recessed as to form the ribbed slugs (a 30 em slug) which is shown after being ejected from the mold and moved forwardly between the usual side trimming knives 31 by the 30 em ejector blade 13.

It will be seen that the front edge of the laterally projecting rib 14 provided on the blade 13 bears against the broad bottom surface 32 of one of the ribs 20 on the slug S, actually against the second rib from the upper end of the slug as viewed in Fig. 3. Such widened bearing of the blade enables advancing the slug squarely out of the mold by overcoming the digging-in and twisting tendency heretofore experienced due to contact only of the thin vertical front edge of an ejector blade against the solid body portion of relatively thick or recessed slugs in which such body portion lies well to one side of the longitudinal center through the slug thickness. Should the length of the casting slot in a selected mold be 26 ems or 18 ems, slugs like the slug S but of these shortened lengths would be cast and for ejecting such slugs the rib-carrying 26 em or 18 em ejector blades 15 or 17 would be selected for use. And should the casting slot in a selected mold be recessed to cast say a 36-point slug, then ejector blades with a similar but narrower lateral rib would be employed and such blades, incidentally, would be suitable as well for ejecting slugs larger than 36-points in thickness.

From the foregoing it will be seen that the invention provides simple and effective means for assuring the satisfactory ejection of recessed slugs of the thicker variety, such means comprising an ejector blade the effective thickness of which is increased at one point in its vertical width by a flange or rib integral therewith and disposed thereon so as to project laterally from a side face of the blade and thus bear squarely against a widened portion of the slug. One only

of such laterally disposed flanges or ribs is sufficient to advance a slug squarely during the ejecting operation, and this even when such rib on the blade engages a widened portion of the slug located toward one end thereof as it does with the ejector mechanism to which the invention is herein applied. Moreover, the invention provides for the accommodation among the blades in a single set thereof of one or more of such rib-carrying ejector blades to suit different slug lengths and for the substitution of ribbed blades for the ordinary plain or non-ribbed blades. It is to be noted, however, that it is preferable for practical reasons to provide the ordinary non-ribbed blades as heretofore in as many sizes (vertical widths) as possible and preferable also to provide such blades in every size where a ribbed blade is also provided, it being evident that the two types of blades function entirely independently, one for the distinct purpose of ejecting relatively thick slugs and the other for ejecting the thinner slugs. Moreover, the arrangement according to the invention lends itself readily to adaptation to any standard machine since in lieu of requiring the introduction of an entirely special form of ejector mechanism, it makes available for use both types of ejector blades merely by substituting in the standard ejector the modified blade guiding member herein described.

I claim:

1. In a slug casting machine, slug ejecting mechanism including a single set of ejector blades of different vertical widths, said blades being arranged side by side in parallel planes in orderly stepped relation according to width and having among them in certain predetermined widths a ribbed and a non-ribbed blade, and a blade confining guide block having stepped surfaces corresponding to the stepped relation of the blades and having a series of clearance slots each for accommodating a rib on a different one of the ribbed blades in the set.

2. In a slug casting machine, slug ejecting mechanism including a single set of ejector blades of different vertical widths and comprising among them in at least one width a ribbed and a non-ribbed blade, said set of blades being arranged in compact relation in parallel planes and in orderly stepped relation according to width, and a blade confining guide block having stepped surfaces corresponding to the stepped relation of the blades and having a slot for accommodating the rib on the ribbed blade in the set.

3. In a slug casting machine, slug ejecting mechanism including an adjustable ejector blade case adapted to contain therein for selective use a single set of ejector blades of different vertical widths and arranged in the case in compact relation flatwise and in orderly stepwise relation as to width, said case being constructed to accommodate within the set and in desired widths blades having a single rib integral therewith and projecting laterally from a side face thereof to thereby increase the effective width of the body portion of such blades at one point in their vertical width.

4. In a slug casting machine, slug ejecting mechanism including a single set of ejector blades of different vertical widths arranged in orderly relation as to width and adjacent facewise in parallel planes, said blades comprising among them in certain predetermined widths a plain blade of uniform thickness throughout its

width and a blade having a single rib projecting laterally from a side face thereof.

5. In a slug casting machine, slug ejecting mechanism including a single set of ejector blades adjustable to select from the set a blade of a desired vertical width, said blades being arranged within the set in orderly relation as to width and adjacent facewise in parallel planes and comprising among them in certain widths only a non-ribbed blade and in certain other widths a non-ribbed blade and a blade having a single rib projecting laterally from a side face thereof at one point in its vertical width.

6. In a slug casting machine, slug ejecting mechanism including a single set of ejector blades of different vertical widths, said blades being arranged adjacent flatwise in parallel planes in orderly stepped relation according to width and having among them plain and rib-carrying blades, and a blade confining guide common to all of the blades in the set and slotted to permit the substitution in certain widths of a ribbed blade for a plain blade.

7. In a slug casting machine, slug ejecting

mechanism including a set of separately selectable ejector blades each of a different vertical width, certain of said blades having integral therewith a laterally projecting rib adapted to increase their effective thickness at one point in their vertical width and said blades being interchangeable with blades in the set of similar width but without such laterally projecting rib.

8. In a slug casting machine, slug ejecting mechanism including a set of ejector blades differing in width and comprising among them ribbed and non-ribbed blades, said blades in similar widths being interchangeable within the set whereby a ribbed blade may be substituted for a non-ribbed blade, or vice versa.

9. In a slug casting machine, slug ejecting mechanism including a single set of ejector blades comprising among them ribbed and non-ribbed blades and said mechanism including means permitting the substitution at given positions within the set of a ribbed blade for a non-ribbed blade.

ARTHUR G. SPERRY.
